UNITED STATES PATENT OFFICE.

CHARLES A. CARMANY, OF SCHAEFFERTOWN, PENNSYLVANIA.

MUSIC-STAND.

1,316,424.

Specification of Letters Patent. Patented Sept. 16, 1919.

Application filed February 4, 1919. Serial No. 274,858.

To all whom it may concern:

Be it known that I, CHARLES A. CARMANY, a citizen of the United States, and a resident of Schaefferstown, county of Lebanon, 5 State of Pennsylvania, have invented certain Improvements in Music-Stands, of which the following is a specification.

One object of my invention is to make a folding music stand which can be extended 10 to accommodate music sheets of different heights.

A further object of the invention is to construct the stand so that the sheet music can be clamped thereto and the music holding portion of the stand and the music can be bodily turned on an axis in order that the 15 musician may read the music on either side of the sheet without detaching it from the stand.

Another object of the invention is to construct the stand so that the music carrying portion can be moved longitudinally and can be readily shifted and turned without 20 binding.

Still another object of the invention is to provide the upper and lower rails of the carrying portion of the stand with clamps for holding the music in position.

In the accompanying drawings:

Figure 1 is a perspective view of my improved music stand, showing it in position to hold sheet music of the ordinary height;

Fig. 2 is a front view, showing the music carrying section extended to its full height;

Fig. 3 is a front view, showing the music carrying section reduced in height to fit the ordinary band march books;

Fig. 4 is a perspective view, showing the parts folded and detached;

Fig. 5 is a sectional view, showing the stand with a music sheet thereon in one position;

Fig. 6 is a view similar to Fig. 5, showing the music carrying section of the stand and 45 the sheet reversed;

Fig. 6^a is a detached view showing a spring washer at one of the joints of the links;

Fig. 7 is an enlarged longitudinal sectional view illustrating the supporting spindle and the sleeve mounted thereon;

Fig. 8 is a detached perspective view of the links connecting the upper and lower

portions of the music sheet supporting section;

Fig. 9 is an enlarged front view, showing the means for holding the sheet supporting section to the spindle;

Fig. 10 is a detached perspective view of a portion of Fig. 9;

Fig. 11 is a modification of the device illustrated in Fig. 10;

Fig. 12 is an enlarged view of one of the clamps for holding the sheet music extended;

Fig. 13 is a sectional view on the line 13—13, Fig. 12;

Fig. 14 is a detached perspective view of one of the clamps and its spring.

1 is the upright portion of a base of an ordinary music stand having a socket 2 at 70 its upper end adapted to receive the end 3 of the supporting spindle 4 on which the sheet music carrying section is mounted. The portion 3 of the spindle 4 is bent as shown, in Fig. 6, forming a spring member 5 so that 75 when this end of the spindle is inserted in the socket it will hold the spindle rigidly in place, but it will allow for the ready withdrawal of the spindle, if desired.

Mounted on the spindle 4 is a sleeve, or 80 tube, 6 extending substantially the full length of the spindle. This sleeve is preferably split at the lower end so as to be frictionally held in the bearing 7 of the lower rail 8 of the music carrying section, 85 Fig. 9. The bearing 9 of the rail 10 of the music carrying section is arranged to slide freely on this sleeve. By this construction, the music carrying section can be readily extended to any height desired without binding 90 on the spindle, therefore the music carrying section can be readily turned on the spindle to reverse the music sheet, when necessary, as it can be moved a slight distance longitudinally to clear a projection 95 on the disk carried by the spindle, which will be described hereafter. A head 4^a on the spindle limits the upward movement of the sleeve which is slotted at the upper end so that it will yield to allow it to pass 100 over the head 4^a when assembling the parts.

Secured to the spindle 4 is a disk 11, acting as a support for the music carrying section. In order to hold the section rigidly in either of its two positions, I provide a cross rib 12, shown in Fig. 10, which extends back

of the lower rail 8 and on which the lower rail rests. When it is desired to shift the music carrying section, it is raised so as to clear the cross rib and then it is turned 5 so that the rail will be back of the cross rib, as in Fig. 6, holding the carrying section in its reversed position.

The upper and lower rails 8 and 10 are connected, in the present instance, by three 10 links 13, 14 and 15, Fig. 8. The link 15 is pivoted at 16 to the upper bar 10 and is held in position by a pin 17 entering a hole in the bar. As this link is only used when music 15 of an extreme height is to be clamped to the section it is not used so frequently as the other links. The link 14 is pivotally connected at 18 to the link 15 and the link 13 is connected at 19 to the lower bar. On the link 13 is a pin 20, which is adapted to a 20 slot 21 in the link 14. This pin has a head and under the head is a spring washer which is sufficiently tight so as to hold the links by friction in any position in which they are set. A set of these links is located at each side 25 of the music carrying section and not only allow the upper rail 10 to move parallel with the lower rail, but also act to support the sheet music between the two rails.

By slotting one of the links, such as 14, 30 and by the use of link 15, an adjustment can be made to accommodate all sizes of concert music sheets so as to allow the sheets to be clamped to the upper and lower rails, without the links obstructing the notes printed 35 on the opposite side of the sheet, so that when the music carrying section is turned with the sheet the notes will not be obstructed.

In Fig. 4, the carrying section is shown 40 removed from the spindle and sleeve and closed; the rails being shown close together, so that the device can be packed into a small carrying case.

In Fig. 3, the carrying section is shown 45 partly extended and of a height to accommodate the ordinary book containing band march music. The links support the body of the book between the rails or bars.

In Fig. 1, I have shown two links 13 and 50 14 extended substantially their full length to accommodate music of the ordinary height.

In Fig. 2, I have shown the carrying section extended to its full height and have 55 illustrated extra links 15. On each rail is a series of spring clamps 22 for holding the sheet music to the rails. Each clamp is preferably made as shown in Figs. 12 to 14, inclusive. The rails are pressed up to 60 form sockets 23 for the pivot pins 24 of the clamps 22 and are pressed in the opposite direction to form sockets 25 for the ends of the spring 26. The central portion of the spring bears against the projecting portion 65 27 of the clamp 22 so as to hold the clamp

in either of its two positions. While I have shown a particular form of clamp, it will be understood that the clamp can be modified without departing from the main features of the invention.

70

In Fig. 11 I have shown a modification of the disk having the cross rib shown in Fig. 10, by providing two pins 12^a which project from the disk 11^a. These pins are preferably tapered and act in substantially 75 the same manner as the rib, but I prefer the rib as being more substantial and easier to manufacture.

It will be seen by the above construction that I am enabled to make a folding music 80 stand in which the music supporting section can be folded in a comparatively small compass and which can be easily extended to accommodate music of different heights. As the clamps form a permanent part of the upper and lower rails of the music carrying 85 section, the music can be clamped to this section so that it will be impossible for currents of air to dislodge the music sheet.

As band march music is never printed on 90 both sides of the sheet the sheets need not be turned, therefore, the links will not obstruct the view when the rails are brought together for clamping a book or sheet of band marches.

95

The concert size music sheet can be clamped to the front of the music carrying section and said section, with the music sheet, can be bodily turned so as to present the other side to the musician, when required. This change of position can be accomplished by merely lifting the music carrying section so as to be clear of the rib 12, after which it can be turned on the spindle and reengaged by the rib, which will hold 105 the stand rigidly in its new position. This can be quickly accomplished with one hand.

100

I preferably use a spring washer 30 at 110 each joint of the links so that the links will be frictionally held in the position to which they are adjusted, and the links can be pivotally connected to the rails and together in any manner desired, without departing from the main features of my invention.

115

I claim:

1. The combination in a music stand, of a supporting spindle; a sleeve mounted thereon; and upper and lower rails of a music carrying section mounted on the sleeve, said sleeve being arranged to turn on the spindle 120 so as to reverse the music carrying section.

2. The combination of a spindle; a sleeve thereon; upper and lower bars of a music carrying section, the lower bar being held on the sleeve, the upper bar being free to 125 be moved longitudinally thereon; and means connecting the upper and lower bars, said sleeve, with the music carrying section, being free to turn on the spindle.

3. The combination of a supporting spin- 130

dle; a long sleeve thereon; upper and lower rails of a music carrying section mounted on said sleeve; links connecting the section so that the upper rail will remain parallel 5 with the lower rail as it is moved toward and from the said lower rail; means for turning the sleeve with the music carrying section on the spindle; and means for holding said sleeve in either of its two positions.

10 4. The combination in a supporting spindle for a music stand, of a sleeve mounted to turn freely on said spindle; a carrying section consisting of upper and lower rails and links connecting the rails, so that the 15 upper rail can be moved toward and from the lower rail and will remain at all times parallel thereto, said rails and links forming the carrying section, the links being connected to the ends only of the rails so as 20 to leave the space between the two rails and between the links open; and means for clamping a sheet of music to the carrying section, the parts being so arranged that the 25 music can be read from either side when the sleeve and the carrying section are turned on the spindle.

5. The combination of a spindle; a disk secured to the lower end of the spindle having a rib; and a sleeve mounted on the spindle above the disk; a music carrying section 30 consisting of upper and lower bars adjustably connected together, the lower bar being frictionally held to the sleeve and the upper bar moving freely thereon, the sleeve 35 having a limited amount of vertical movement on the spindle so that it can be raised clear of the rib and turned with the music carrying section.

6. The combination in a supporting spindle, of a sleeve mounted thereon; upper and lower rails of a music carrying section mounted on the sleeve; two links arranged in series connecting the upper rail with the lower rail at each end thereof, the upper 45 rail being free to be moved toward and from the lower rail and frictionally held in position by the links.

7. The combination of a spindle; a sleeve thereon; upper and lower rails of a music 50 carrying section mounted on the sleeve, the lower rail being held to the sleeve, the upper rail being free to move thereon; and three links arranged in series connecting the upper rail with the lower rail at each end thereof, one end of the third link of each 55 set being removably held to one of the rails.

8. The combination in a music stand, of a

supporting spindle; a sleeve thereon; a music carrying section consisting of upper and lower angular rails extending parallel with 60 each other and mounted on the sleeve, the upper rail being connected to the lower rail and movable in respect thereto; a series of spring clamps carried by one of the angular members of each rail and arranged to 65 clamp the sheet music against the other member of each rail so as to hold the music firmly to the carrying section while said section is being turned on the spindle.

9. The combination in a music stand, of 70 a spindle adapted to be mounted in a base; a sleeve on the spindle; a music carrying section consisting of two angular cross bars and connecting links, the lower cross bar being held to the sleeve by friction, the upper 75 cross bar being arranged to slide on the sleeve and held in the position to which it is adjusted by frictional engagement of the connecting links; a disk on the spindle having a rib against which the lower cross bar 80 rests, the sleeve being free to move vertically on the spindle to allow it to be turned with the music carrying section to reverse the music; and a series of spring clamps on the cross bars for holding the music 85 firmly to the cross bars so that it can be turned with the music carrying section.

10. The combination in a music stand, of upper and lower rails, said rails being slotted for the reception of spring clamps, each 90 clamp having pivot pins and a projection beyond the pivot pins, each rail being pressed up at each side of the slot to form sockets for the pivot pins and also pressed in the opposite direction to form sockets; 95 and springs adapted to the sockets extending under the clamp and bearing upon the projections thereon so as to hold the clamp in either of its two positions.

11. The combination of a rail having a 100 bearing portion and a slotted portion at right angles to the bearing portion, said rail being pressed up to form sockets at each end of each slot and depressed beyond these projections to form bearings for a spring; a 105 slotted metallic spring clamp having a pivot pin at each side mounted in the slot, the pins extending into the bearings; and a spring located in the depressions and bearing upon the heel of the clamp so as to hold 110 the clamp in either of its two positions.

In witness whereof I affix my signature.

CHARLES A. CARMANY.
